UNITED STATES PATENT OFFICE.

CHARLES G. BACON, OF ANTIGO, WISCONSIN, ASSIGNOR OF ONE-HALF TO EDWARD HADLER,
OF ANTIGO, WISCONSIN.

COMBINED SHADE AND CURTAIN-POLE SUPPORT.

No. 872,637.

Specification of Letters Patent.

Patented Dec. 3, 1907.

Application filed June 24, 1907. Serial No. 380,506.

To all whom it may concern:

Be it known that I, CHARLES G. BACON, a citizen of the United States, residing at Antigo, in the county of Langlade and State 5 of Wisconsin, have invented certain new and useful Improvements in a Combined Shade and Curtain-Pole Support; and I do declare the following to be a full, clear, and exact description of the invention, such as will 10 enable others skilled in the art to which it appertains to make and use the same.

This invention relates to improvements in combined shade and curtain pole supports.

The object of the invention is to provide 15 a support of this character which may be applied to a window frame without the use of separate fastening devices, and by means of which a curtain pole and shade roller may be supported and firmly held in proper position.

With this object in view, the invention consists of certain novel features of construction, combination and arrangement of parts 20 as will be more fully described and particularly pointed out in the appended claims.

In the accompanying drawings, Figure 1 is a plan view of my improved support applied to a window frame, showing the shade roller and curtain pole engaged therewith; 25 Fig. 2 is a side elevation of the same; and Fig. 3 is a detail perspective view of one of the supports.

Referring more particularly to the drawing, 1 denotes my improved shade roller and 30 curtain pole brackets or supports, each of which is formed from a single wire rod, which is bent substantially midway between its ends to form a loop or depression adapted to receive the lug or projection, 3, on the 35 castings which are secured to the opposite ends of the shade roller.

The rods 1 are bent upwardly at their outer ends to form curtain pole supports 4, which may be engaged with transversely dis-

posed holes, 5, formed in the curtain poles 45 adjacent to their opposite ends, or may serve as stops to hold the curtain pole on the rods 1 when said poles are not provided with holes to receive the supports 4.

The rods 1 are provided on their inner ends 50 with screw-threads, 6, by means of which the same may be conveniently screwed into window frame, thus providing for the attachment of the same without the use of separate fastening devices. This arrangement also 55 dispenses with the necessity of any form of tool for applying the supports to the window frame.

Having thus fully described my invention, what I claim as new and desire to secure by 60 Letters-Patent, is:

1. A combined curtain pole and shade support, comprising a continuous rod member having intermediate of its inner and outer ends a substantially U-shaped bent portion 65 adapted to form a socket for the reception of one of the trunnions of the shade roll, the said rod having its outer end adapted to be passed through an opening in a curtain pole and provided beyond said point with means 70 for the effective retention of said rod in said opening.

2. A continuous rod having intermediate of its end portions a substantially downwardly bent U-shaped portion, forming a 75 socket for the reception of the trunnion upon one end of the shade roll, said rod having its outer end bent upwardly to form a stop at that point, and a curtain pole having a transverse opening therethrough for the reception 80 of said rod.

In testimony whereof I have hereunto set my hand in presence of two subscribing witnesses.

CHARLES G. BACON.
